UNITED STATES PATENT OFFICE

JAMES A. OURSLER, OF STEUBENVILLE, OHIO, ASSIGNOR OF ONE-HALF TO GEORGE OURSLER, OF CINCINNATI, OHIO

RETAINING WALL STRUCTURE

Application filed November 29, 1927. Serial No. 236,535.

This invention relates to a retaining wall structure and has for its object the provision of a retaining structure which is self-anchoring and which furthermore relieves the material of the structure of earth pressure.

Another object is to provide a device of this kind which is simple of construction and which is exceptionally efficient in that in the event of a land slide which would bury and completely cover the retaining structure, the structure itself would be neither displaced nor damaged so that the mere clearing away of the earth and débris will again place the adjoining property to be protected in good condition without entailing the expense of building a new retaining wall.

These and other objects are attained by the means described herein and disclosed in the accompanying drawing, in which:

20 The figure represents a fragmental perspective view, partly in cross section and partly broken away of a retaining wall in an operative position.

In practicing the hereinafter described invention a hillside 1 to be supported to prevent sliding onto an adjacent highway 2 is excavated slightly at a suitable distance from its base to strike a shale or stone stratum 3. The natural stratum 3 is used as a foundation for the base of a suitable trench 4. Below the level of the highway 2 a second trench 5 is constructed for receiving the base of the reinforcing structure. The trenches 4 and 5 therefore extend in parallelism and are disposed at different elevations. The space between the trenches 4 and 5 is then cleared of dirt and soil which is replaced with rock ballast 6 retained, if necessary by a suitable vertical form, not shown, so that

40 it may be filled up to a level with the top of trench 4 adjacent the inner edge of said trench, and to a higher level above the trench 5. In the trench 5 are placed longitudinally extending reinforcing bars 7 of suitable steel and about these bars 7 are anchored the turned or curved ends 8 of spaced vertical reinforcing bars 9 which extend for a distance above the top of the rock ballast where they are bent angularly at 10 toward and into the trench 4, the angle of such bend be-

ing approximately 20 degrees from the horizontal. A suitable form work is used to extend in spaced parallelism with the upright bars 9 and bent over portions 11 and the entire form filled with concrete to form a reinforced vertical wall 12 with an integral inclined slab 13 terminating in a longitudinal concrete beam 14 formed in the trench 4. The dimensions of the wall will be proportional to the estimated load which they would have to support in the event of a land slide.

55 It will be noted that the trench 5 provides base extensions 15 and 16 of concrete at the bottom of vertical wall 12. The extension 15 may be covered and additionally anchored by extending the highway road bed over it. The angle of the slab portion 13 is such that the weight of earth which it supports produces a vertical downward thrust thereon. The body of the slab is supported by the loose rock ballast, and at its innermost edge is anchored upon the firm natural stone or shale of the hillside which will not slide. The outermost end is supported upon the vertical wall 12. Inasmuch as the pressure of the weight of earth above cannot exert a tipping force upon the wall, said wall and slab structure, even though of apparently scanty dimension will successfully withstand any land slide without being broken or displaced. In the event of an extremely heavy land slide such as may occur in terrific storms, the volume of moving earth may be such as to flow over the edge 17 of the wall and possibly bury the wall. This would have no 60 damaging effect upon the firmly anchored retaining structure which continues in service after clearing away the over flow of earth and débris.

65 It will be understood that the width of the slab 13 between the forward edge 17 and the rear of the trench 4 and the height of the wall 12 from the trench 5 to the top edge 17 will be governed by the factors of location of a firm rock or shale foundation for the beam 14 and the estimated possible amount of landslide to be governed. In all such constructions however the angle of approximately 20 degrees is maintained between the slab 13 and wall 12 so that the re- 70 75 80 85 90 95 100

taining structure cannot be wedged outwardly and displaced or tipped over onto the highway or joining property. In most localities wherein such structures are required, the ballast material 6 is found in abundance in the hillsides to be retained. The wall 12 is preferably located with its inner wall at the base of the existing grade so that the amount of excavation necessary for the erection of the retaining structure is comparatively small. After the retaining structure is complete the falling earth will establish a new grade of lesser declivity upon the top of the slab 13 whereupon the earth slippage will be substantially arrested except for natural erosion and emergency such as excessive rainfall and storm.

The advantages of the herein described structure over the heretofore used retaining means including simple tapered concrete walls, stone walls, piles and the like resides in the fact that the structure of this invention cannot be washed out, tipped over or in any way destroyed or displaced as in the previously mentioned means. The heretofore used retaining structures seldom withstand the combined effects of the elements for more than two years, and frequently require complete removal and rebuilding after heavy storms and washouts. The structure of this invention on the other hand is practically permanent, since the weight of additional land slides serves to anchor it more firmly in position.

35 What is claimed is:

1. In a retaining structure for hillsides and the like comprising a vertical reinforced concrete wall having at its top an integral reinforced slab portion extending into the hillside and anchored therein, the slab portion of the structure being downwardly inclined toward the hillside at such angle as to direct weight thereon into a downward pressure which serves to anchor the structure more firmly in position, the reinforced slab extending uninterruptedly throughout the length of the vertical wall.

2. In a retaining wall structure comprising a vertical concrete wall enlarged at its base, horizontal reinforcing members in the enlarged base and wall, transverse reinforcing members anchored about the vertical members and downwardly inclined from the top of the wall, and an integral concrete slab having the turned portion of the reinforcing members embedded therein extending into the hillside, the reinforced slab extending uninterruptedly throughout the length of the vertical wall.

60 3. A retaining wall structure comprising a reinforced concrete construction having an inverted substantially J-shaped cross section, the base of said structure being disposed at the base of a hillside, and the opposite end thereof being anchored in a solid portion of

the hillside to be retained, and ballast disposed in and filling the space between the base and anchored edge of the structure, the reinforced slab extending uninterruptedly throughout the length of the vertical wall.

4. A retaining structure comprising a vertical wall and an integral slab extending from the top thereof at an angle of substantially 70 degrees, the slab extending the entire length of the vertical wall.

5. An earth retaining structure comprising a reinforced concrete vertical wall having a T-shaped base and an integral slab inclined from the top of the wall and terminating in an enlarged beam parallel therewith, the reinforcing members of said structure extending from said beam through the slab and wall into the base, the slab extending the entire length of the vertical wall.

6. A retaining wall for a hillside comprising a vertical wall and an integral uninterrupted flange co-extensive with the vertical wall, inclined thereto at an angle of about 70 degrees and means for anchoring the edge of the flange in the hillside at an elevation from the base of the vertical wall.

7. A retaining structure for a hillside comprising a pair of integral uninterrupted wall members inclined from one another at substantially 70 degrees and having the free edges of said walls buried in the hillside, the space between the walls being filled with ballast comprising substance of the body of the hillside.

In testimony whereof, I have hereunto subscribed my name this 21st day of November, 1927.

JAMES A. OURSLER.
